UNITED STATES PATENT OFFICE

ALEXANDER KALLA, OF LINDEN, NEW JERSEY

WINDOW

Application filed June 25, 1931. Serial No. 546,838.

The present invention relates to new and useful improvements in windows and has for its primary object to provide, in a manner as hereinafter set forth, a window embodying a novel construction, combination and arrangement of parts whereby the upper and lower sashes are adapted for vertical sliding movement or swinging movement in a vertical plane for permitting greater ventilation through the window and to facilitate the washing of the glass in both sashes on both sides from the interior of the building.

Other objects of the invention are to provide a window of the character described which will be simple in construction, strong, durable, weatherproof when closed and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in vertical cross section through a window in accordance with this invention showing both sashes raised and swung to open position.

Figure 2 is a fragmentary view in elevation showing one side portion of the window looking at the same from the interior of the building.

Figure 3 is a vertical cross sectional view through the window showing the sashes in closed position.

Figure 4 is a fragmentary view in horizontal cross section through one side portion of the window showing both sashes in lowered position and ready to be swung inwardly.

Figure 5 is a view in perspective of one of the sashes.

Figure 6 is a fragmentary detail view in horizontal cross section through one of the side portions of the sashes.

Figure 7 is a detail view in perspective of one of the pin supporting straps which are mounted on the upper portions of the sashes.

Referring now to the drawings in detail, it will be seen that the window constituting

the present invention comprises a frame which is designated generally by the reference numeral 1, said frame including a sill 2, a stool 3, the vertical side members 4 and a top cross member 5. Adjacent each end the upper cross member 5 is provided with a pair of slots in which pulleys 6 are journaled.

The opposed faces of the side members 4 of the frame 1 are stepped in the manner illustrated to advantage in Figure 4 of the drawings and secured thereon are the guide strips 7 which, in conjunction with said side members 4, define vertical channels 8. The inner edges of the strips 7 are provided with notches or recesses 9, the purpose of which will be presently set forth. The outer marginal portions of the opposed faces of the side members 4 also have secured thereon the vertical strips 10.

Upper and lower sashes 11 and 12, respectively, are mounted for sliding and swinging movement in the frame 1 and to this end said sashes each have secured on their side edges at their upper portions the metallic strips 13 which are countersunk in said sashes and which are provided with in-turned lower end portions 14 (see Figure 7) which are embedded in the sashes. The upper end portions of the strips 13 are apertured and anchored therein are the headed pins 15 upon which are journaled the hooks 16. Ropes or cables 17 have counterweights 18 suspended from one end and have their other ends engaged with the hooks 16 for connecting said ropes or cables to the sashes. The ropes or cables 17 are trained over the pulleys 6. The pins 15, together with the hooks 16 and the ropes or cables 17 travel in the channels 8 of the frame 1. It will be noted that the upper sash 11 is of less width than the lower sash 12 and it will also be noted that the sashes are of a width which will permit the same to be swung inwardly and upwardly between the strips 7 of the frame 1. The upper sash 11 is slidably engaged with the strip 10 on each of the side members 4 when in a vertical position.

The pins 15, being disposed in the channels 8, provide an axis upon which the sashes 11 and 12 may be swung inwardly and upwardly. Lugs 19 project from

100

the lower vertical side portions of the sashes 11 and 12 and are disposed for travel in the channels 8 when said sashes are moved vertically in the frame 1. The lugs 19 are operable through the passages 20 provided therefor in the lower portions of the strips 7 when it is desired to swing the sashes in a vertical plane. The lugs 19 of the sash 11 are of a length to permit the same to pass the inner strips 7 when said sash 11 is swung in a vertical plane.

10 The intermediate portions of the vertical side edges of the sashes 11 and 12 are recessed for the reception of the pivoted supporting arms 21, the free ends of which are engageable in the notches 9 of the strips 7 for supporting the sashes in the raised position which is illustrated to advantage in Figure 1 of the drawings. The lower portions of the side members 4 of the frame 1 are provided with openings in which are disposed removable closure plates 22 through the medium of which access may be had to the counterweights 18 when desired.

15 In use, the sashes 11 and 12 may be slid vertically in the frame 1, the pins 15 and the lugs 19 traveling in the channels 8 for maintaining said sashes in a vertical position. When it is desired to swing the sashes in a vertical plane, said sashes are disposed in the frame in a position to align the lugs 19 with the passages 20 after which the sashes may 20 be swung inwardly and upwardly and raised to the desired elevation.

25 30 It is believed that the many advantages of a window constructed in accordance with the present invention will be readily understood, and although the preferred embodiment of the invention is as illustrated and described, it is to be understood that changes 35 in the details of construction and in the combination and arrangement of parts may be resorted to which will fall within the scope 40 of the invention as claimed.

45 The sashes 11 and 12 may be expeditiously removed from the window frame by simply disposing said sashes in a substantially horizontal position and then tilting the same in a manner to disengage the pins 15 from their 50 respective channels. Another advantageous feature of the invention resides in the fact that the sashes may be swung inwardly and upwardly to an almost inverted position for disposing the outer sides of the glass panes 55 inwardly for the purpose of washing the same.

What is claimed is:—

60 A window comprising a frame, said frame including vertical side members having stepped opposed faces, strips secured on said opposed faces of the side members and, in conjunction therewith, defining channels, said strips having transverse passages in their lower portions, upper and lower sashes 65 mounted for sliding and swinging movement

in a vertical plane in the frame, pins on the upper side portions of the sashes disposed for travel in the channels for guiding the sashes vertically in the frame, lugs projecting from the lower side portions of the sashes and disposed for travel in the channels, said lugs being operable through the passages when the sashes are swung in a vertical plane, the upper sash being of less width than the lower sash, said sashes being operable between the strips when swung in a vertical plane, the strips having notches therein, and supporting arms pivotally mounted on the sashes and engageable in the notches for supporting the sashes in upwardly swung position.

70 75 80 In testimony whereof I affix my signature.

ALEXANDER KALLA.
